PUMP

Philip Lane Scott, San Mateo, Calif., assignor to
 Super Diesel Tractor Corporation, La Porte,
 Ind., a corporation of New York

Application October 20, 1930, Serial No. 489,744

10 Claims. (Cl. 103—150)

This invention relates to a pump and particularly to a pump adapted to deliver a small quantity of fluid under great pressure and with great speed.

5 It has for one object to provide a pump in which the mechanical shock due to the movement of the pump and its driving mechanism is reduced to a minimum. Another object is to provide a pump in which sliding surfaces within 10 the pressure chamber are eliminated. Another object is to provide a pump in which the walls or a part of the walls of the pump chamber are elastic.

Other objects will appear from time to time in 15 the specification and claims.

The invention is illustrated more or less diagrammatically in the accompanying drawing, wherein—

Figure 1 is a cross section through the pump, 20 showing the inlet and outlet valves;

Figure 2 is an elevation of the pump, showing in part the operating means.

Like parts are designated by like characters throughout specification and drawing.

25 A is a pump body or housing that is preferably provided in one face with a raised land A¹ which co-operates to form a depression or chamber A². A³ is a cavity formed in the pump body A and provided adjacent one end with an inwardly extending shoulder or reduced portion A⁴. An inlet valve housing may be seated in the cavity A³. A⁵ is another cavity formed in the body portion A and provided adjacent one 30 end with a shoulder or reduced portion A⁶. An outlet valve housing may be positioned within the cavity A⁵ and may rest against the shoulder or reduced portion A⁶. Extending through the body portion A and communicating with the 35 pump chamber and with the outside of the pump is an air vent A⁷. A⁸ is a controlling valve therefore, preferably provided with a handle or manipulating part A⁹ by means of which it may be moved into and out of position to control the air 40 vent. The air vent, while it may be placed in any suitable location, is preferably in an extension A¹⁰ formed as a part of the valve body.

45 Removably secured to the valve body A is a retaining portion B of generally annular shape. It may be fastened to the valve body by screws B¹ or by any other suitable means.

50 Lying between the pump body A and the retaining member B and compressed against the land A¹ of the pump body is a disc or diaphragm C. It together with the pump body A completes

the pump chamber A². This diaphragm may be made of any suitable material and although I have shown it as being laminated and thus made of a plurality of members, it might be made of a single member. Whatever its details of construction and form it is essentially an extremely stiff diaphragm.

Supported from and preferably made integral with the retaining member B is a support D. This support is in effect a loop provided with oppositely placed parts which are fastened to the annulus B and provided with a portion joining these two, so that it thus provides a loop over the valve disc or diaphragm.

E is a compression plate positioned against the 70 diaphragm C. It is provided with one generally flat face which lies against the diaphragm and it is somewhat rounded or tapered away adjacent its edges as at E¹. On its opposite face it carries a boss E² and a helical race E³. Tapered rollers 75 E⁴ are mounted to run in the helical race E³.

F is a rocking member provided with a depression F¹ which is seated upon the boss E². The rocking member is provided on one face with a helical race F² and on its opposite side 80 with a flat race F³ within which tapered rollers F⁴ are positioned and adapted to move. At one edge and extending outwardly from the rocking member F is a pair of ears F⁵, F⁶. Positioned between the ears is a drive rod or shaft F⁷ which may be moved by any suitable mechanism back and forth, as indicated by the arrow in Figure 2. F⁸ is a boss formed on the member F, opposite the depression F¹.

G is a bearing supporting member resting upon the boss F⁸ of the member F and provided with a flat bearing race G¹. The member G rests against the support D.

H is an inlet valve housing adapted to be seated in the cavity A³ in the pump body A. 95 It is provided with a bore H¹ which has at one end a valve seat portion H². H³ is a valve positioned within the bore H¹ and carrying a head H⁴ adapted to be seated in the seat H². A spring H⁵ bearing at one end upon the valve and at the other upon the diaphragm C tends to hold the valve seated.

I is an outlet valve housing provided with a bore I¹ which terminates in a reduced portion I² and has a seat I³ adjacent the reduced portion. I⁴ is a valve formed with a point I⁵. The valve is positioned within the bore I¹ and the point is adapted to be seated in the seat I³. I⁶ is a spring tending normally to hold the valve seated. The valve housings may be held in the 110

position shown by any suitable means, such for example as clamps, or they might be threaded into the valve body.

It will be realized that while I have herewith shown and described a practical operative device, nevertheless many changes might be made in the size, shape, number and disposition of parts without departing from the spirit of my invention and I wish, therefore, that my showing be taken as in a sense diagrammatic. Particularly the form of the housing and the means for compressing or moving the diaphragm might be widely changed, as might also particular structural details of the several other parts of the device.

The use and operation of the invention are as follows:

With the parts assembled as shown, it is assumed that the diaphragm or disc C is lying in a natural or flat position and that fluid is within the pump chamber. A heavy and preferably sudden pressure is exerted upon the diaphragm to force it inward by movement of the shaft or rod F⁶, which movement causes the rocking member F to move and the compression member or washer E is forced against the diaphragm as a result of the motion of the rocking member which turns through a portion of a revolution and causes the rollers which engage it to ride upon the helical race formed on the back of the member E and on the face of the rocking member F. The side of the rocking member away from the diaphragm has a flat face which serves merely as a thrust bearing, the other face of which is formed by the member G. This movement of the rocking member F is imparted to the diaphragm C, as explained, and forces it inwardly, thus reducing the volume of the pump chamber, creating pressure within it and forcing open the outlet valve and discharging fluid from the pump.

After the discharge stroke the rocking member is moved in the reverse direction and the member E is permitted to fall back from the diaphragm as a result of the reverse movement given the rocking member with its helical race. The diaphragm may then spring or move outwardly again, thus increasing the volume of the pump chamber, permitting or causing the outlet valve to close, creating a suction which opens the inlet valve and draws a fuel charge into the pump chamber. Thus a suction stroke is completed and the pump cycle consists of the alternate compression and expansion or inward and outward movement of the diaphragm in response to the wedging action which is communicated to it by the movement of the rocking member F.

The yielding member or members of the pump chamber of this invention is subject to strains well within its elastic limit. The pump chamber is enclosed by walls wholly or in part approximately rigid, capable of minutely yielding and preferably of returning to their original position of their own elasticity when free to do so. If parts of the wall are not approximately rigid, they are rigid.

In order to assure proper operation of the rocking member F with relation to the compression plate E, the latter is preferably provided with some mechanism for preventing its turning with relation to the other parts and in the form shown herewith the member is slotted or provided with a depression in its edge, into which a pin which is fixed in the ring B projects.

I claim:

1. In combination in a pump, a housing portion defining a pump chamber, and a member fixed to said housing, and means for flexing said member to alter the volume of the pump chamber, the flexing means including a wedge member adapted to exert pressure upon said member.

2. In combination in a pump, a housing portion defining a pump chamber, and a member fixed to said housing and means for flexing said member to alter the volume of the pump chamber, said member adapted of itself to return to its original position when free to do so, the flexing means including a wedge member adapted to exert pressure upon said member.

3. In combination in a pump, a housing portion defining a pump chamber, and an approximately rigid member fixed to said housing, and means for flexing said approximately rigid member to alter the volume of the pump chamber, said approximately rigid member adapted of itself to return to its original position when free to do so, the flexing means including a wedge member adapted to exert pressure upon said approximately rigid member.

4. In combination in a pump, a housing portion defining a pump chamber, and a member fixed to said housing, and means for flexing said member to alter the volume of the pump chamber, the flexing means including a rotary wedge member adapted to exert pressure upon said member.

5. In combination in a pump, a housing portion defining a pump chamber, and an approximately rigid member fixed to said housing, and means for flexing said approximately rigid member to alter the volume of the pump chamber, said approximately rigid member adapted of itself to return to its original position when free to do so, the flexing means including a rotary wedge member adapted to exert pressure upon said approximately rigid member.

6. In combination in a pump, a rigid housing portion partially defining a pump chamber, and an approximately rigid member fixed to said housing and partially defining the pump chamber, and means for flexing said approximately rigid member to alter the volume of the pump chamber, said approximately rigid member adapted of itself to return to its original position when free to do so, the flexing means including a rotary wedge member adapted to exert pressure upon said approximately rigid member.

7. In combination in a pump, a housing portion defining a pump chamber, and a member fixed to said housing, and means for flexing said member to alter the volume of the pump chamber, said member adapted of itself to return to its original position when free to do so, the flexing means including a wedge member adapted to exert pressure upon the approximately rigid member, said wedge member having one generally helical bearing race.

8. In combination in a pump, a housing portion defining a pump chamber, and a member fixed to said housing, and means for flexing said member to alter the volume of the pump chamber, said member adapted of itself to return to its original position when free to do so, the flexing means including a wedge member adapted to exert pressure upon the approximately rigid member, there being roller bearings in contact with said wedge member, said wedge member having one generally helical bearing race.

9. In combination in a pump, a housing portion defining a pump chamber, and a member fixed to said housing, and means for flexing said member to alter the volume of the pump chamber, said member adapted of itself to return to its original position when free to do so, the flexing means including a rotary wedge member adapted to exert pressure upon the approximately rigid member, said wedge member having one generally helical bearing race.
10. In combination in a pump, a housing portion defining a pump chamber, a member fixed to said housing and means for flexing said member to alter the volume of the pump chamber, said member adapted of itself to return to its original position when free to do so, the flexing means including a rotary wedge member adapted to exert pressure upon the approximately rigid member, there being roller bearings in contact with said wedge member, said wedge member having one generally helical bearing race.

PHILIP LANE SCOTT.
